STAND FOR DRESS-FORMS AND THE LIKE

Ralph F. Palmer, Montclair, N. J., assignor to The Singer Manufacturing Company, Elizabeth, N. J., a corporation of New Jersey

Application June 12, 1951, Serial No. 231,193

7 Claims. (Cl. 223—120)

1

The present invention relates to stands for dress-forms and the like, of the type set forth in the U. S. Patent of Ray et al., No. 2,284,967. The primary object of the present invention is to provide such a stand which is fully satisfactory in operation but which can be manufactured and sold at a much lower cost than similar devices heretofore made.

A more specific object of the present invention is to provide an improved cross-head for a dress-form stand that adjustably supports the cross-arms, which cross-head can be manufactured more inexpensively than prior devices without detracting from the usefulness or efficiency of it.

Having in mind these and other objects that will be evident from an understanding of this disclosure, a presently preferred embodiment of the invention is hereinafter set forth in such detail as to enable those skilled in the art to readily understand the function, operation, construction and advantages of it, when read in conjunction with the accompanying drawings, in which:

Fig. 1 is a side elevational view of a stand including a cross-head that embodies the teachings of this invention, with the dress-form supported thereby shown in vertical section.

Fig. 2 is a section view taken substantially on the line 2—2 of Fig. 1 with the dress-form removed.

Fig. 3 is a fragmentary vertical section view taken substantially on the line 3—3 of Fig. 2.

Fig. 4 is a fragmentary section view taken on the line 4—4 of Fig. 1.

Fig. 5 is a perspective view of the cross-head body member with the hub secured thereto.

Fig. 6 is a fragmentary vertical section view taken substantially on the line 6—6 of Fig. 2.

Fig. 7 is a plan view of the blank of sheet metal which is to be bent to form the body member of the cross-head.

Fig. 8 is a perspective view of one of the locking levers.

With reference to the drawings, the illustrated embodiment of my invention includes a base 1 from which rises a vertical standard 2 carrying at its upper end a wire, dress-form supporting, neck-frame 3. A dress-form 4 is hung upon and supported by the neck-frame 3, the lower end or skirt portion of the dress-form being secured against lateral movement relative to the standard 2 by a skirt-support 5.

The base 1 comprises a substantially cylindrical hub 6 formed of heavy metal to render the stand more stable, and from which radiate three bent metal legs 7, equally spaced angularly about

the hub. The legs 7 may be secured to the hub 6 in any convenient manner, but are preferably made detachable so that the stand may be readily knocked-down. The vertical standard 2 consists of a hollow tube 8 that is detachably secured in a central bore of the hub 6 as by a set screw, not shown, and a rod 9 that is telescopically received in the tube 8. The rod 9 is secured in vertically adjusted position relative to the tube 8 by a clamp 10 that is fixed to the upper end of the tube.

The above construction is fully set forth in my copending U. S. patent application, Serial No. 145,801, filed Feb. 23, 1950, and it is therefore deemed to be unnecessary to expand this disclosure in relation thereto.

The skirt support includes a tubular hub 11 adapted to slidably receive the rod 9 of the standard 2 and which is adapted to be secured to the rod 9 in vertically adjusted position by means of a clamp, generally designated 12, fixed thereto. As more clearly seen in Fig. 6, the ends of the hub 11 are flared outwardly and reduced to form shoulders 13 and thin-walled ends 14. The clamp 12, which is substantially the same as clamp 10, is formed from a single blank of sheet metal and includes a rectangularly shaped back 15. Upper and lower platforms 16 and 17, respectively, are bent from the short edges of the rectangular back 15 at substantially right angles thereto. The clamp 12 thus appears generally C-shaped in vertical section. Apertures 18 and 19 are provided in the platforms 16 and 17, respectively. The aperture 19 is of such size as to slidably receive the rod 9 and the aperture 18 is large enough to be fitted over one of the reduced ends of the hub 11. The reduced end 14 is upset, as clearly shown in Fig. 6, to secure the clamp 12 to the hub 11.

The clamp 12 is provided with two spring-biased levers 20 and 21 which serve to hold it in adjusted position on the rod 9, each lever serving as a one-way stop. The levers 20 and 21 project through slots formed in the back 15 and are themselves apertured at the ends which project through the back 15 to receive a cotter-pin 22 to pivotally mount the levers on the back. The levers 20 and 21 are also apertured to slidably receive the rod 9 and are biased away from each other by a spring 23, the outward movements of the levers causing them to bind on the rod 9. The spring 23 preferably surrounds the apertures in the levers, and also surrounds the rod 9 when the clamp is positioned on the rod. It will be noted that by this binding action, the upper lever 20 will prevent the clamp 12 from moving down-

wardly on the rod 9 and the lower lever 21 will prevent upward movement of the clamp 12 on the rod 9. In order to raise the clamp, the lever 21 is manually pivoted to a horizontal position against the action of the spring 23, which eliminates the binding action of the lever 21 and releases the clamp 12 for movement. In order to lower the clamp on the rod 9, the lever 20 is moved to a horizontal position. To facilitate the manual manipulations of the levers 20 and 21, they are provided with fingers 24 and 25, respectively, which project to a point where they can be readily grasped. Motion-limits are provided for the levers against which they can be held in a horizontal or rod-releasing position. These limits are formed as fingers 26 on side portions 27 of the clamp 12. The sides 27 are bent from the longer edges of the rectangular back 15 at substantially a right angle thereto and to the same side as the platforms 16 and 17. The levers 20 and 21 are enlarged transversely adjacent the apertures therein to extend beyond the sides 27, as more clearly seen in Fig. 2. These enlarged edges of the lever will abut against the fingers 26 when the levers are moved toward each other, and when thus held against the fingers, the levers will be in rod-releasing position, permitting the clamp 12 to be freely moved on the rod 9.

In assembling the clamp 12, after the platform 16 has been secured to the hub 11 by upsetting the adjacent reduced end 14, the levers 20 and 21 are positioned with the apertured ends thereof projecting through the slots in the back 15. The cotter pin 22 is then passed through the apertures in the projecting end, after which the spring 23 is placed in position. Outward movement of the levers 20 and 21 is limited by the binding produced between them and the walls of the slots in the back 15. The clamp is thus in a stable assembled condition.

A cross-head body member preferably provided with a substantially square central bore portion 28 having an aperture 29 located centrally thereof, is secured to the opposite end of the hub 11 from the clamp 12 in a manner similar to that in which the clamp 12 is secured to the hub, i. e., the reduced end 14 of the hub projects through the aperture 29 and is then upset. The edges of the base portion 28 are extended to form clamp-bases 30 which, in the preferred form, are four in number, substantially rectangular and equally spaced angularly about the base portion 28. Along the outer edges of the clamp-bases 30, the cross-head blank is bent at substantially a right angle to form side-plates 31. Ears 32 and 33 are bent inwardly toward the central portion 28 from the side edges of the depending portions 31 at substantially right angles thereto.

The ears 32 and 33 are provided with square apertures 34 and 35, respectively, transversely aligned with respect to each other in each pair of ears, to receive the cross arms 36 and 37, which are provided in pairs, the pair 37 being longer than the pair 36. The longer arms 37 are adapted to engage the dress form 4 across its width and the shorter arms 36 are adapted to engage the dress form across its depth. The arms 36 and 37 are provided with arcuately bent outer ends which carry rubber fenders 38 to insure a firm but non-damaging contact with the dress-form. To preclude turning of the arms in the apertures 34 and 35, they are made square to cooperate with the square configuration of the apertures.

With particular reference to Fig. 2, it will be seen that in the preferred embodiment of my in-

vention the clamp bases 30 are not formed as planar extensions of the base portion 28 of the cross-head body but that the opposite parts of the clamp bases lie in planes parallel to but spaced above and below the plane of the base portion 28. This spacing is made sufficient to place the pairs of cross-arms in different planes and thus to provide a clearance so that the arms will not interfere with each other.

In order to secure the cross-arms in the desired, adjusted position, four spring clamps are provided, one for each of the cross-arms. However, since all the clamps are identical, for the sake of brevity, only one will be described. Each of the spring clamps comprises a lever 39 (Fig. 8) centrally apertured to slidably receive a cross-arm, and biased into binding engagement with that cross-arm by means of a spring 40. The lever 39 is pivotally mounted in a depending manner on the clamp base 30 by a reduced neck portion 41 of the lever which extends through a slot 42 in the clamp base 30. The slot is elongated so that in placing the lever in position, it is only necessary to insert the end through the elongated slot and give it a quarter-turn. The spring 40, which normally surrounds a cross-arm, abuts against the lever 39 at one end and against the ear 33 at the other. A circularly-shaped depression 43 is formed in the ear 33 from the center of which is punched the aperture 35, which depression serves as a seat for the spring 40. The lever 39 is similarly provided with a spring seat. Thus, the spring 40 biases the lever 39 to one side and into a binding engagement with the cross-arm inserted in the aperture in the lever, which locks the cross-arm against movement in the one direction, unless the lever is manually moved to and held in an arm-releasing position. The cross-arm is at all times freely movable in the opposite direction.

A substantially V-shaped slot extends inwardly from the outer, free edge of the depending portions 31; one edge 44 of the slot being substantially normal to the outer edge of the clamp base, and the other edge 45 being inclined thereto. A similar slot including a normal edge 46 and inclined edge 47 is formed in the ear 32. In the fully developed condition, as shown in Fig. 5, the slot in the ear 32 bent from the adjacent clamp base 30 lies directly opposite the slot in the depending portion and cooperates therewith in order to form motion-limits for the lever 39. The lever 39 is enlarged transversely adjacent the cross-rod aperture therein to such an extent as to extend into both the slots in the depending portion 31 and ear 32. When the cross-rod is removed, the spring 40 urges the lever against the edges 45 and 47 of the slots, which facilitates assembling the cross-head. With the cross-arm in position, the lever 39 may be readily placed in arm-releasing position by moving it into engagement with the edges 44 and 46. It will be noted that the pivot slot 42 in the clamp base 30 is so positioned relative to the normal edges 44 and 46 that the lever will be substantially normal to the cross arm when in engagement with the edges 44 and 46 and thus in arm-releasing position.

When the cross-arms are inserted in the cross-head, as shown in Fig. 2, they are so placed in a selected relationship that the clamping levers 39 must be moved to arm-releasing position to admit them. Thus, the cross-arms may be readily moved outwardly against the inner walls of the dress-form 4 and will be automatically

locked in this adjusted position by the levers 39 to hold the lower or skirt-portion of the dress-form against movement relative to the vertical standard 2.

The cross-head body, as hereinbefore stated, is formed from a single blank of sheet metal. The blank, as it is punched out, appears as shown in Fig. 7, in which figure the lines along which the blank is to be subsequently bent are shown as dotted.

From the present disclosure it will be seen that the cross-head may be readily formed by simple manufacturing steps readily adapted to mass production methods. The cross-head can, therefore, be produced and sold at a much lower cost than has heretofore been possible. It will also be noted that the economy produced has in no way detracted from the function or utility of the cross-head.

Numerous alterations and changes of the structure disclosed herein will suggest themselves to those skilled in the art. However, it is to be understood that the present disclosure relates to a preferred embodiment of my invention which is for purposes of illustration only and not to be construed as a limitation of my invention. All such modifications which do not depart from the spirit of my invention are intended to be included within the scope of the appended claims.

Having thus set forth the nature of the invention, what I claim herein is:

1. A cross-head for a dress-form stand or the like including a body member formed from a single blank of sheet metal and having a base portion provided with a standard-receiving aperture, a plurality of clamp-bases extending from the periphery of the base portion, side-plates bent from the extremities of the clamp-bases, and pairs of ears bent inwardly from the transverse edges of the side-plates to underlie the clamp-bases; a clamping-lever provided for each of said clamp-bases and pivoted thereto at one end, said ears and clamping-levers being apertured to receive cross-arms, and a spring interposed between each of the clamping-levers and a corresponding one of each of the pairs of said ears to bias the clamping-levers into binding engagement with the respective cross-arms inserted therethrough.

2. A cross-head for a dress-form stand or the like including a body member formed from a single piece of sheet metal and having a base portion provided with a standard-receiving aperture, a plurality of side plates carried by the base portion and inclined thereto, said side-plates being provided with pairs of transversely aligned apertures, the apertures in each pair being located in opposite side-plates, a clamping-lever adjacent each side-plate and pivotally carried by the base portion, the longitudinal axis of the clamping-levers lying on a plane substantially parallel to the plane of the respective side-plate, each of said clamping-levers having apertures aligned with a pair of apertures in the side-plates, cross-arms inserted through the aligned apertures, and springs adapted to bias the clamping-levers into binding engagement with the respective cross-arms inserted therethrough.

3. A cross-head for a dress-form stand or the like including a body member formed from a single blank of sheet metal and having a base portion provided with a standard-receiving aperture, a plurality of clamp-bases extending from the periphery of and substantially in the plane of the

base portion, said clamp-bases being substantially equally spaced angularly about the center of the base portion, side-plates bent from the extremities of the clamp-bases at substantially right angles thereto, and pairs of ears bent inwardly from the transverse edges of the side-plates to underlie the clamp-bases and to lie substantially normal thereto; a clamping-lever provided for each of said clamp-bases and pivoted thereto at one end, said ears and clamping-levers being apertured to receive cross-arms, and a spring interposed between each of the clamping-levers and a corresponding one of each of the pairs of said ears to bias the clamping-levers into binding engagement with the respective cross-arms inserted therethrough.

4. A cross-head for a dress-form stand or the like including a body member formed from a single blank of sheet metal and having a base portion provided with a standard-receiving aperture, a plurality of clamp-bases extending from the periphery of the base portion, side-plates bent from the extremities of the clamp-bases, and pairs of ears bent inwardly from the transverse edges of the side-plates to underlie the clamp-bases; a clamping-lever provided for each of said clamp-bases and pivoted thereto at one end, said ears and clamping-levers being apertured to receive cross-arms, a spring interposed between each of the clamping-levers and a corresponding one of each of the pairs of said ears to bias the clamping-levers into binding engagement with the respective cross-arms inserted therethrough, whereby the cross-arms will be releasably locked against movement in the one direction, and stops for limiting the pivotal movement of the clamping-levers, one of said stops for each clamping-lever being so arranged that the clamping-lever will be in arm-releasing position when abutting thereagainst.

5. A cross-head for a dress-form stand or the like including a body member formed from a single blank of sheet metal and having a base portion provided with a standard-receiving aperture, a plurality of clamp-bases extending from the periphery of the base portion, side-plates bent from the extremities of the clamp-bases, and pairs of ears bent inwardly from the transverse edges of the side-plates to underlie the clamp-bases, a corresponding one of the ears of each pair being elongated to further underlie a part of the base portion, a clamping-lever provided for each of said clamp-bases, said clamping-levers being pivoted at one end to the clamp-bases, said ears and clamping-levers being apertured to receive cross-arms, a spring interposed between each of the clamping-levers and a corresponding one of each of the pairs of said ears to bias the clamping-levers into a binding engagement with the respective cross-arms inserted therethrough whereby the cross-arms will be releasably locked against movement in the one direction, transversely aligned slots formed in each side-plate and the elongated ear bent from the adjacent side-plate, said clamping-levers having transversely enlarged mid-portions that project through the respective slots, whereby the slots will serve as motion-limits, one of the limit-positions for each clamping-lever being so arranged that the clamping-lever will be in arm-releasing position when held therein.

6. A cross-head for a dress-form stand or the like comprising a hub adapted to slidably receive a vertical standard and having reduced ends, a clamp adapted to secure the hub to the standard

in vertically adjusted position and having a standard-receiving aperture therein, a body member having a base portion provided with a standard-receiving aperture, said reduced ends of the hub projecting through the standard-receiving apertures of the clamp and base portion and being upset to secure the same together, said base portion further comprising a plurality of clamp-bases extending from the periphery of the base portion, side-plates bent from the extremities of the clamp-bases, and pairs of ears bent inwardly from the transverse edges of the side-plates to underlie the clamp-bases, a clamping-lever provided for each of said clamp-bases, and pivoted thereto at one end, said ears and clamping-levers being apertured to receive cross-arms, and a spring interposed between each of the clamping-levers and a corresponding one of each of the pairs of said ears to bias the clamping-levers into binding engagement with the respective cross-arms inserted therethrough.

7. In combination with a stand for dress-forms or the like having a base, a vertically disposed standard rising from the base, a dress-form supporting neck-frame supported on the upper end of the standard, and a cross-head adjustably se-

5 cured on the standard and adapted to carry cross-arms engageable with the inner surface of the dress-form to secure it against lateral movement relative to said standard, said cross-head comprising a hub having reduced ends surrounding the standard, a clamp having a standard-receiving aperture adapted to be secured to the standard in vertically adjusted position, a body member formed from a single piece of sheet metal 10 and having a base portion centrally apertured to slidably receive the standard, one of said reduced ends of the hub projecting through the aperture in the clamp and the other projecting through the aperture in the base portion, said reduced ends being upset to secure the parts together.
